CLAIM

The ornamental design for a cookware liner, as shown and described.

DESCRIPTION

FIG. 1 is a bottom perspective view of a cookware liner; FIG. 2 is a rear perspective view of the cookware liner shown in FIG. 1;

FIG. 3 is a front elevational view thereof;

FIG. 4 is a top plan view thereof;

FIG. 5 is a rear elevational view thereof;

FIG. 6 is a right side elevational view thereof; and,

FIG. 7 is a bottom plan view thereof.

A left side elevational view is not shown because it is the mirror image of the right side elevational view shown in FIG. 6.

The ornamental design which is claimed is shown in solid lines in the drawings.
